UNITED STATES PATENT OFFICE.

ALFRED J. EBNER, OF CHICAGO, ILLINOIS, ASSIGNOR TO FREYN, BRASSERT & COMPANY, OF CHICAGO, ILLINOIS, A CORPORATION OF MAINE.

FIRE-TUBE BOILER.

Application filed January 15, 1923. Serial No. 612,637.

This invention relates to a new and improved fire tube boiler and more specifically to a boiler provided with means introduced into the boiler flues adapted to increase the heat transfer and to provide means for cleaning the flues.

The present invention has particular relation to boilers of the type designed to utilize waste heat from other apparatus such, 10 for example, as open hearth furnaces. These boilers are provided with flues through which pass the highly heated products of combustion from the furnace.

Relatively high velocity is to be desired 15 in the movement of the gases passing through the flues since with slow velocity the colder gases tend to remain adjacent the wall of the tube or flue with a consequent failure to utilize the heat of the central 20 portion of the gases. With high velocity there is a more thorough dispersion and equalization between the hot and cold gases. Further, in boilers of this type, there is a considerable accumulation of dust and solid 25 matter of various kinds in the flues. It is necessary, therefore, for efficient operation, that the tubes be periodically cleaned or blown out.

It is an object of the present invention to 30 provide means comprising members adapted to be located in the flues, said means causing the heated gases to be passed into contact with the flue walls and to be caused to move at a greater velocity due to the restricted 35 area of passage.

It is a further object to provide means 40 of this character which are so constructed and connected as to be adapted for the introduction of steam or gas under pressure to blow out the foreign matter accumulating in the flues.

Other and further objects will appear as the description proceeds.

I have illustrated a preferred embodiment 45 of my invention in the accompanying drawings, in which—

Figure 1 is a fragmentary vertical section showing the invention applied to a waste heat boiler;

50 Figure 2 is a section on an enlarged scale showing one of the flues, with the inserted cylinder shown in elevation;

Figure 3 is a section taken on line 3—3 of Figure 2; and

Figure 4 is a view on an enlarged scale 55 showing the flue and cylinder in section.

Referring first to Figure 1, the waste heat boiler 11 is connected by passage 12 to the open hearth furnace or other source from which heated gases may be drawn. The 60 boiler is connected by passage 13 with a stack or other means for carrying off the gases. The boiler as shown is provided with the steam connection 14. The flues 15 of the boiler are each provided with a cylindrical member 16 which extends throughout the greater portion of the length of the flue. These members 16 are tubular and are connected to the steam header 17, which latter is controlled by valve 18. The tubular member 16, shown more in detail in Figures 2 to 4, is provided with the lugs 19 which engage the inner walls of the flue 15 as best shown in Figure 3. As is apparent from the drawing, said lugs 19 present substantially no obstruction to the flow of gases 70 through the flues.

As shown in Figure 4, the tubular members 16 are provided with the openings 20 which are inclined in the direction of the normal 80 flow of the gases through the flues.

The members 16 remain permanently in the flues and during the normal operation of the furnace, they serve to cause the gases to be directed against the inner flue walls, thus 85 facilitating the transfer of heat. They also increase the necessary velocity of the gases since they reduce the available passage area.

When it is desired to blow the soot or other foreign matter from the flues, it is 90 only necessary to open valve 18 when the steam entering the member 16 is directed against the flue walls through openings 20. The direction of the jets of steam passing through the openings is toward the stack 95 end of the flues and the foreign matter is effectively blown from the flues in the direction of the stack.

While I have shown one preferred embodiment of my invention, it is obviously capable of modification to meet varying conditions. It is my intention to cover all such changes and modifications as come within the scope of the appended claim.

I claim:

In combination, in a boiler, tubular flues of substantially uniform diameter extending therethrough, tubes of substantially uniform

diameter mounted in said flues, said tubes being provided with spacing means for holding same in spaced relation with the inner walls of said flues, said spacing means comprising lugs disposed around the periphery of each of said tubes and being formed to provide substantially no obstruction to flow in the space between said tubes and their

corresponding flue walls, said tubes being provided with openings through the walls thereof, said openings being inclined in the direction of the normal flow in said tubes.

Signed at Chicago, Illinois, this 11th day of January, 1923.

ALFRED J. EBNER.
